DESIGN FOR A BEVERAGE DISPENSING DEVICE

Everett Worthington, Chicago, Ill., assignor to The Coca-Cola Company, Atlanta, Ga., a corporation of Delaware

Application July 20, 1933. Serial No. 48,764

Term of patent 14 years

To all whom it may concern:

Be it known that I, EVERETT WORTHINGTON, residing at Chicago, in the county of Cook and State of Illinois, have invented a new, original, and ornamental Design for a Beverage Dispensing Device, of which the following is a specification, reference being had to the accompanying drawings, forming part thereof.

Figure 1 is a front elevation of my new beverage dispenser;

Fig. 2 is a side elevation thereof;

Fig. 3 is a top plan view thereof;

Fig. 4 is a bottom plan view thereof; and

Fig. 5 is a rear elevation.

I claim:

The ornamental design for a beverage dispensing device, as shown.
